UNITED STATES PATENT OFFICE.

CYRUS M. DAVIDSON, OF KANSAS CITY, MISSOURI.

BALING-PRESS.

No. 796,116.

Specification of Letters Patent.

Patented Aug. 1, 1905.

Application filed July 11, 1904. Serial No. 216,184.

To all whom it may concern:

Be it known that I, CYRUS M. DAVIDSON, a citizen of the United States, residing at Kansas City, in the county of Jackson and State of Missouri, have invented certain new and useful Improvements in Baling-Presses, of which the following is a specification.

My invention relates to improvements in baling-presses; and one of my objects is to obtain a maximum stroke of the plunger in order to obtain a large feed-opening with a minimum stroke of the trip-lever.

A further object is to obtain a tensile strain on the mechanism employed to advance the plunger, and thus avoid the loss of power usually accompanying this operation when the customary pitman is employed owing to said pitman bending more or less under the compressive strain to which it is subjected.

Other objects of the invention will hereinafter appear, and in order that said invention may be fully understood reference will now be made to the accompanying drawings, in which—

Figure 1 represents a broken plan view of a press embodying my invention, a portion of it being in section taken on line I I of Fig. 2. Fig. 2 is an enlarged side elevation of the power end of the press. Fig. 3 is a vertical transverse section of the same, taken on line III III of Fig. 1. Fig. 4 is an enlarged broken side elevation of the rear portion of the press, showing the operation of a cam, toggle, and plunger forming part of the invention. Fig. 5 is a vertical transverse section taken on line V V of Fig. 2, showing how a pair of rails forming a guide-track are supported.

In said drawings, 1 designates a hopper through which hay is fed into the baling-chamber 2, provided with the usual retainers 3 and connected to the power end of the press by a bed-plate 4, constructed of angle-irons bolted at their forward ends to a gooseneck 5. Said gooseneck is secured at its top and bottom portions to a transverse frame 6, comprising upright castings 7, cross-bars 8, secured to the ends of the upright portions, and centrally disposed cast-iron blocks 9 and 10, secured between bars 8. Vertical portions 7 are provided at their lower ends with stub-axles 11, mounted in a pair of wheels 12, which, in conjunction with a pair of wheels 13, mounted upon a rear axle 14, form portable supports for the press.

13^a designates a trip-lever provided at its opposite ends with the usual antifriction-roll-

ers 14^a and formed integral with a centrally-disposed vertical shaft 15, provided at its upper end with an integral cross-head 16, to which a sweep 17 is secured to which the team is hitched. Shaft 15 is journaled in block 9 and the upper and lower portions of the gooseneck, said lower portion being provided with a tapering boss 18, which rests in a tapering socket 19 in the central portion of block 10. The lower portion of shaft 15 is reduced to form a shoulder 19^a, which rests upon the lower portion of the gooseneck. The upper portions of the gooseneck and frame 6 are braced to resist the strains imposed thereon when the trip-lever is in operation by means of a brace comprising a pair of brackets 20, secured side by side upon the bed-plate, tie-rods 21 connecting the upper ends of the brackets to the rear upper portion of the gooseneck and gas-pipes 22 inclosing the rods and abutting at their opposite ends against the brackets and the gooseneck. (See Fig. 2.) The upper ends of the brackets are braced by a transverse bar 20^a, secured to rods 21 by taps 21^a.

23 designates a pair of laterally-projecting arms formed integral with one side of the gooseneck.

25 designates a chain secured at its forward end to a rod 26, secured at its forward end to a pair of bars 27, pivotally secured at their forward ends by a bolt 28 to a pair of bars 29, rigidly secured near their forward ends to a block 30, against the rear face of which rollers 14^a are adapted to contact, bars 29 being far enough apart to permit the trip-lever to pass between them.

31 designates a pair of segmental arms pivotally connected at their opposite ends to arms 23 and bars 29 to prevent the latter from swinging away from the trip-lever when one of rollers 14^a is in engagement with block 30.

32 designates a roller interposed between the forward ends of bars 27 and journaled upon bolt 28.

33 designates a pair of parallel rails arranged on opposite sides of roller 32 and secured at their opposite ends to brackets 20 and an inverted-L-shaped casting 34, bolted upon one of the angle-irons forming the bed-plate.

The rear end of chain 25 is attached to a pin 35, forming the pivotal point of a toggle 36, comprising a casting 37, rigidly secured at one end to shaft 38 and pivotally secured at its opposite end to pin 35, and a pair of arms 39, pivotally secured at their opposite ends to

pin 35, and a plunger 40, reciprocably arranged in the baling-chamber.

Shaft 38 is journaled in bearings 41 and provided at its extended end with a rigidly-mounted crank-arm 42, to the lower end of which a retractile spring 43 is attached, said spring being connected at its opposite end to one end of a chain 44, the opposite end of which is adjustably secured to a hook 45 in order that the tension of spring 43 may be regulated.

Plunger 40 is caused to move forward in an opposite direction to the block 30 and with increasing power by a cam 46, mounted upon a shaft 47, journaled at its opposite ends in bearings 48. Cam 46 has a low radius 49 at one end, a high radius 50 at its opposite end, and an intermediate radius 51, connecting 49 and 50, as shown in Fig. 4. It also has a peripheral groove 52 for the reception of the rear portion of chain 25, secured to the cam by a hook-bolt 53.

54 designates a recess in the cam to prevent the latter from contacting with shaft 38 when occupying the dotted position shown in Fig. 4. The cam extends through a slot 55, provided in the casting 37 to prevent the cam from conflicting therewith.

When toggle 36 is in the extended position shown by full lines, Fig. 4, all tendency of its becoming locked, and thus preventing the quick rebound of the plunger, is overcome by a retractile spring 56, attached at its opposite ends to an eyebolt 57 and a chain 58, which latter is attached at its lower end to pin 35. Eyebolt 57 is secured to the intermediate portion of a brace 59, extending from one end of hopper 1 for the support of the upper end of an arch 60, extending upwardly from the bed-plate to protect the outside horse from contacting with the toggle when the latter swings back to the folded position shown by dotted lines, Fig. 4.

In operation one of rollers 14^a contacts with block 30 at the point shown by dotted lines, Fig. 1, and as the trip-lever rotates it advances said block, which is held in engagement with the trip-lever by arms 31 until bars 29 almost contact with shaft 15, when the engaging roller 14^a passes out of engagement with block 30. As the block advances it straightens out toggle 36 through the instrumentality of chain 25 and the cam over which said chain operates, and thus causes the plunger to advance and compress the charge of hay. The initial movement of the plunger will be comparatively fast and accompanied with but little power, because chain 25 is then pulling around the low radius of the cam; but as the plunger nears the end of its forward stroke its power is increased and speed diminished by the high radius of the cam rotating into contact with chain 25. The instant the trip-lever disengages the block the plunger will rebound until it contacts with stop-blocks 61,

owing to the expansive force of the compressed hay and the retractile power of springs 43 and 56. The forward and backward movements of chain 25, rod 26, and bars 27 will be in a direct line owing to roller 32 traveling between guide-rails 33, and in order that bars 29 may be brought almost in alinement with bars 27 when the latter are at the end of their forward movement the trip-lever shaft 15 is set to one side of the center of the bed-plate, as shown in Fig. 1, and in order to obviate the necessity of the front ends of bars 29 from swinging outwardly with the trip-lever far enough to exert much side draft the bearing-surface of block 30 is made sufficiently long to prevent accidental disengagement of the contacting roller 14^a. The advantage of thus operating these bars in practically a direct line is obvious and requires no further explanation.

In order that block 30 may be adjusted to properly coöperate with the plunger and trip-lever, the forward end of rod 26 is provided with a plurality of bolt-holes 26^a for the reception of bolts 26^b.

Having thus described my invention, what I claim, and desire to secure by Letters Patent, is—

1. In a baling-press, a plunger, a toggle pivotally secured at its opposite ends to the press-frame and said plunger, a cam journaled upon the press-frame near said toggle, a cable attached to the joint of said toggle and engaging the periphery of the cam, means for retaining the cable in engagement with said periphery throughout the movement of said cam, and means for pulling said cable to advance the plunger.

2. In a baling-press, a plunger, a toggle pivotally secured at its opposite ends to the press-frame and said plunger, a cam journaled upon the press-frame near said toggle, a cable attached to the joint of said toggle and engaging the periphery of the cam, means for retaining the cable in engagement with said periphery throughout the movement of the cam, means for pulling on said cable to extend the toggle and advance the plunger, and means to assist in folding said toggle after it has been extended.

3. In a baling-press, a plunger, a toggle pivotally secured at its opposite ends to the press-frame and said plunger, a cam journaled upon the press-frame near said toggle, a cable attached to the joint of said toggle and engaging the periphery of the cam, means for retaining the cable in engagement with said periphery throughout the movement of the cam, means for pulling on said cable to extend the toggle and advance the plunger, and a retractile spring attached to the joint of the toggle and an upper portion of the press to assist in folding said toggle after it has been extended.

4. In a baling-press, a plunger, a shaft journaled on the press-frame in the rear of said

plunger, a toggle pivotally secured at its forward end to the plunger and rigidly secured at its rear end to said shaft, a crank-arm rigidly mounted upon one end of said shaft, a retractile spring attached to its opposite ends to the free ends of said crank-arm and the press-frame, a second shaft journaled upon the press-frame between the first-mentioned shaft and the plunger, a cam mounted upon said second shaft, a cable attached to the joint of the toggle and engaging the periphery of the cam, means for retaining the cable in engagement with said periphery throughout the movement of said cam, and means for pulling on said cable to advance the plunger.

5. In a baling-press, a plunger, a toggle pivotally secured at its opposite ends to the press-frame and said plunger provided with a slotted arm, a cam journaled upon the press-frame which extends through the slotted arm of the toggle and has a low radius, a high radius, and an intermediate radius connecting the low radius and the high radius; a cable attached to the joint of the toggle and engaging the periphery of said cam, means for retaining the cable in engagement with said periphery throughout the movement of said cam, and means for pulling on said cable to advance the plunger.

6. In a baling-press, a rod, a pair of bars adjustably secured to the forward end of said rod, a second pair of bars pivotally secured at their rear ends to the forward ends of the first-mentioned bars, a block secured to the forward ends of the second pair of bars, a trip-lever journaled upon the forward portion of the press-frame, adapted to engage said block and advance the rod, a plunger, and means connecting the rod to said plunger whereby the latter is simultaneously advanced with said rod.

7. In a baling-press, a rod, a pair of bars adjustably secured to the forward end of said rod, a second pair of bars secured at their rear ends to the forward ends of the first-mentioned bars with a bolt, a block secured to the forward ends of the second pair of bars, a trip-lever journaled upon the forward portion of the press-frame, adapted to engage said block and advance the rod, arms projecting laterally from one side of the press-frame, arms pivotally secured at their opposite ends to said laterally-projecting arms and the forward ends of the second pair of bars, a plunger, and means connecting the rod to said plunger whereby the latter is simultaneously advanced by said rod.

8. In a baling-press, a rod, a pair of bars adjustably secured to the forward end of said rod, a second pair of bars secured at their rear ends

to the forward ends of the first-mentioned bars with a bolt, a block secured to the forward ends of the second pair of bars, a roller mounted upon said bolt, a pair of parallel rails secured to the press-frame between which the roller travels, a trip-lever journaled upon the forward portion of the press-frame adapted to engage the block and advance the rod, a plunger, and means connecting the rods to said plunger whereby the latter is simultaneously advanced with said rod.

9. In a baling-press, a rod, a pair of bars adjustably secured to the forward end of said rod, a second pair of bars secured at their rear ends to the forward ends of the first-mentioned bars with a bolt, a block secured to the forward ends of the second pair of bars, a roller mounted upon said bolt, brackets secured upon the press-frame, an inverted-L-shaped casting secured upon the press-frame, a pair of parallel rollers between which the roller travels secured at their opposite ends to said brackets and the L-shaped casting, a trip-lever journaled upon the forward portion of the press-frame adapted to engage the block and advance the rod, a plunger, and means connecting the rod to said plunger whereby the latter is simultaneously advanced with said rod.

10. In a baling-press, a transverse frame at the forward portion thereof, centrally-disposed blocks at the top and bottom of said frame the lower block having a tapering socket, a gooseneck having a tapering boss on its lower portion which fits into the socket, and a trip-lever journaled in the gooseneck and the upper centrally-disposed block and provided with a shoulder which rests upon the lower portion of the gooseneck.

11. In a baling-press, a transverse frame at the forward portion thereof, centrally-disposed blocks at the top and bottom of said frame, the lower block having a socket, a gooseneck having a boss on its lower portion which fits into said socket, a trip-lever journaled in the gooseneck and the upper centrally-disposed block provided with a shoulder which rests upon the lower portion of said gooseneck, brackets secured to the press-frame, tie-rods connecting the upper rear portion of the gooseneck to the upper ends of said brackets, and gas-pipes inclosing said tie-rods and abutting at their opposite ends against the gooseneck and the brackets.

In testimony whereof I affix my signature in the presence of two witnesses.

CYRUS M. DAVIDSON.
